UNITED STATES PATENT OFFICE

HARRY C. HAGMAN, OF MINNEAPOLIS, MINNESOTA, ASSIGNOR TO HENRY P. BOOS, OF
MINNEAPOLIS, MINNESOTA

ATTACHING DEVICE FOR DENTURES

Application filed October 26, 1927. Serial No. 228,776.

My invention relates to attaching devices for use in attaching removable dentures to permanent teeth and has for its object to provide a device in which a minimum amount of wear occurs due to movement of the denture in mastication caused by the yielding of the gum tissue on which the denture is supported.

Another object of the invention resides in providing an attaching device comprising a flange with a web issuing outwardly therefrom in providing wing-like portions on said web with a flange disposed on either side of said web with a cylindrical post secured to said web and parallel with said flange, and in further providing a slit sleeve adapted to embrace said post and slide freely thereon together with shoulders disposed along the edges of said sleeve formed by said slit and adapted to abut against said wing-like portion.

Another object of the invention resides in constructing said shoulder with spaced kerfs to divide the same into sections adapted to be independently brought together to compensate for different degrees of wear along the attaching device.

With the foregoing and other objects in view, which will appear in the following description, the invention resides in the novel combination and arrangement of parts and in the details of construction hereinafter described and claimed.

In the drawings:

Fig. 1 is a fragmentary view of the human maxilla projected upon the occlusal plane with a number of the molars previously extracted.

Fig. 2 is a view similar to Fig. 1 illustrating a double denture applied to take the place of the missing molars and employing my improved attaching device.

Fig. 3 is a plan view of the denture illustrated in Fig. 2 removed from the maxilla.

Fig. 4 is an enlarged detail view of a portion of the denture and the permanent teeth to which the same is attached illustrating the application of my invention thereto.

Fig. 5 is an elevational view of the lingual side of the structure shown in Fig. 4.

Fig. 6 is a perspective view of my improved

attaching device prior to application to a denture.

In the use of removable dentures such as bridges, partial plates, etc., and particularly where the denture is supported upon gum tissue, considerable wear occurs on the attaching structure. This is particularly true with tube and post attaching members, such as are now in common use. My invention overcomes this objectional characteristic of such structures by providing shoulders on the sleeve or tubular member adapted to prevent rotational movement, and further adapted to co-operate with the post flange to resist wear as the teeth are used in mastication.

For the purpose of illustrating the application of my invention I have shown in Figs. 1 and 2 a portion of the human mandible 10 having incisors 11, canines 12 and bicuspids 13 and 14. In the particular specimen illustrated, the remaining teeth have been previously extracted to expose the gums, as at 15 and 16.

For the purpose of supplying the lost teeth of the mandible indicated at 10, I have shown two partial plates 17 and 18 having bicuspids 19 and 20 and molars 21 adapted to rest upon the gums 15 and 16 so as to take the place of the teeth previously extracted, the said plates 17 and 18 being connected by a lingual band 22.

The invention proper consists of two attaching members which are attached to the permanent bicuspids 13 and 14 and the bicuspids 19 and 20 of the denture, and are shown in detail in Fig. 6. These attaching members each comprise a male member 31 and a female member 32 adapted to be connected together to firmly support the structure attached thereto. The male member 31 consists of a flange 23 formed with a web 24 issuing outwardly from the center of said flange to provide wing-like portions 25 and 26 disposed to either side of said web. Along the web 24 is constructed a cylindrical post 27 which is spaced from the flange 23 and lies parallel thereto. Operating in conjunction with the post 27 I employ a sleeve 28, which sleeve is slit along an element thereof so as to permit the sliding of the same over said post, the

- slit portion allowing the passage of the web 24 through said sleeve. At the extreme edges 29 of said sleeve caused by the slitting thereof are formed shoulders 30 which may be constructed by soldering pieces of triangular wire to the said edges of the sleeve or which may be constructed integral therewith. It will be noted that the flange 23 is slightly curved so as to more readily fit the surface of the teeth to which it is to be applied and that also the shoulders 30 are correspondingly curved so as to cause the same to at all times lie in contact with the wing-like portions 25 and 26 of said flange 23.
- 15 In the use of the device the permanent bicuspids 13 and 14 are preferably crowned or provided with inlays which have attached to them the male members 31. The flanges 23 of said members are soldered thereto and are so arranged relative to the crown or inlay as to be flush with the surface thereof, leaving only the web 24 and post 27 protruding from the same. The particular arrangement of this structure can best be seen in 25 Figs. 1 and 4, flange 23 being illustrated in dotted lines in Fig. 4. In a similar manner the sleeves 28 are soldered to the metal connected with the band 22 so that the same occupy the proper position relative to the 30 posts 27. With this arrangement, the entire denture may be bodily removed from the patient's mouth by sliding the female members 32 along the male members 31 in a direction away from the gums 15 and 16.
- 35 In the application of my invention to dentures, the male member 31 and the female member 32 are preferably arranged in slightly inclined direction with reference to the occlusal plane so that upon applying pressure 40 to the denture in the mastication of food, the shoulders 30 are caused to bear upon the wing-like portions 25 and 26 of the flanges 23 as the gum tissue supporting the plates 17 and 18 yield. This brings all of the wear 45 in the attaching member upon the said shoulders and flanges. Due to the width of the same, the wear is greatly minimized and the life of the structure is greatly prolonged. With dentures such as shown in Fig. 3 a certain degree of oscillatory movement of each 50 of the plates 17 and 18 occurs relative to the post 27 due to the lateral movement of the jaw occasioned in normal mastication. With the ordinary type of post attaching member, wear at the slit in the sleeve occurs very rapidly due to the fact that but a small area is presented to resist such oscillatory movement and due to the further fact that it is impossible to construct and maintain the edges 55 of the sleeve in firm contact with the web of the male member. With my invention, the shoulders formed on the edges of the sleeve formed by the slit thereof are greatly reinforced and present appreciable surfaces 60 which minimize the wear and resist the os-

cillatory movement of the female member upon the male member.

For the purpose of compensating for whatever little wear occurs with my improved attaching member, I have constructed the shoulders 30 with a number of kerfs 33 in the edges of the same as best shown in Fig. 6 dividing the shoulder up into several individual sections 34 integrally connected with the sleeve portions 28. With this arrangement the individual sections can be separately clinched together to close the bore through the sleeve 28 and to further bring the shoulders 30 in contact with the flange 23. With this arrangement different portions of the said shoulders may be adjusted to correspond with the degree of wear received by them so that the attaching member may at all times be maintained with the said shoulders in positive contact with the flanges of the male member throughout their extent.

My invention is highly meritorious in that it provides a simple and effective device for reducing the wear on the attaching members or removable dentures, and at the same time provide a device whereby the denture is firmly and securely held in the mouth of the patient. My invention permits the connection between the male and female member of the attaching structure to move relative to one another to compensate for the compression of the gums during mastication, the thrust upon the members being taken up through the shoulders and flanges of said members during such action. The device can be constructed at a cost hardly exceeding that of the ordinary attaching member, and when properly applied leaves no visible indication of the same.

Changes in the specific form of my invention, as herein disclosed, may be made within the scope of what is claimed without departing from the spirit of my invention.

Having described my invention, what I claim as new and desire to protect by Letters Patent is:

1. In combination with a permanent tooth and a removable denture adjacent thereto and resting upon gum tissue of a flange secured to said permanent tooth, a post connected to said flange and parallel therewith, a slit sleeve secured to said removable denture and adapted to embrace said post, shoulders formed on said sleeve adapted to bear against said flange, said post and sleeve being inclined relative to the occlusal plane in such a direction as to cause said shoulders to bear against said flange upon occlusal movement of the removable denture relative to the permanent tooth occasioned by the yielding of the gum tissue.

2. In combination with a permanent tooth and a removable denture adjacent thereto and resting upon gum tissue, of a flange secured to said permanent tooth, a post con-

nected to said flange and parallel therewith, a slit sleeve secured to said removable denture and adapted to embrace said post, shoulders formed on said sleeve adapted to bear against said flange, said sleeve and post being free at both ends to permit of the free sliding of the one relative to the other, said post and sleeve being inclined relative to the occlusal plane in such a direction as to cause said shoulders to bear against said flange upon occlusal movement of the removable denture relative to the permanent tooth occasioned by the yielding of the gum tissue.

3. In combination with a permanent tooth and a removable denture adjacent thereto and resting upon gum tissue, a member secured to said permanent tooth, a second member secured to said denture and being slideable relative to said first member in a direction toward and from the gum, means for guiding said members throughout the movement thereof, said members being formed with bearing surfaces inclined relative to the direction of movement of said denture, to cause said bearing surfaces to receive the strain imparted to the denture upon occlusion so as to remove the strain from said guiding means.

In testimony whereof I have affixed my signature to this specification.

HARRY C. HAGMAN.
